Primary Examiner — Marissa J Cash(74) *Attorney, Agent, or Firm* — Abelman, Frayne & Schwab(57) **CLAIM**

The ornamental design for an aircraft wing flap fairing, as shown and described.

DESCRIPTION

FIG. 1 is a bottom, front, right side perspective view of an aircraft right-side wing flap fairing showing our new design, the aircraft left-side wing flap fairing being a mirror image thereof;

FIG. 2 is a bottom, rear, left side perspective view thereof;

FIG. 3 is a front elevation view thereof;

FIG. 4 is a right elevation view thereof;

FIG. 5 is a left elevation view thereof;

FIG. 6 is a bottom view thereof; and,

FIG. 7 is a rear elevation view thereof.

1 Claim, 2 Drawing Sheets(56)
